DEVICE FOR CONVERTING ELECTRIC OSCILLATIONS INTO MECHANICAL VIBRATIONS

Application filed December 16, 1927, Serial No. 240,571, and in the Netherlands February 18, 1927.

This invention is concerned with a device such as is used in telephones, loudspeakers and the like for converting electric oscillations into mechanical vibrations.

5 According to the invention a ferromagnetic element, i. e., an armature, which is adapted to be subjected to the influence of electric oscillations, is arranged so as to move within and in the direction of two parallel 10 but opposite magnetic fields. The armature is supported by having its ends secured to a resiliently mounted frame.

It is easier to support the frame than to support the armature and the frame is also 15 more accessible which permits the springs to be arranged at any point and in any number desired. If the frame is moved in a determined manner the armature is forced by the stiff construction of the frame to move in the 20 same manner and vice versa. The probability of the armature receiving, in addition to said movement in a determined direction, another movement about its own axis is therefore negligible because of such rigid 25 construction but it constitutes a source of danger in devices in which the ends of the armature are each directly secured to a spring support because the freedom of movement of the armature is thus increased.

30 According to the present invention the frame may be rectangular in form with the armature connected to two parallel sides of the frame, the middles of the other two sides being secured to the spring supports.

35 If the frame is supported by unilaterally clamped springs the points of clamping of the springs may be located on the same side relatively to the axis of movement of the armature. The springs being caused to proceed in the same direction as the armature, the latter will receive a substantially rectilinear movement but will not move about its own axis.

40 If the springs are clamped unilaterally the restoring force exerted by them will proceed in line with the deviation of the armature. The magnetic force is known to change quadratically to this deviation so that the resultant repulsive force is not proportional to the 45 deviation of the armature. If, however, the

armature is caused to move through very small distances, substantially proportionate resultant forces will ensure through the said distances.

The loudspeaker may be particularly sensitive when the springs are very slack which however entails the probability that the armature will come into contact with and adhere to the magnet. 55

According to the invention the frame has 60 fixed to it one or more wires or chords which prevent the armature from receiving any undesirably great movement and from contacting with the poles.

The accompanying drawings illustrate a 65 construction embodying the invention. In the said drawings:

Figure 1 is a side view of a magnet system embodying the invention.

Figure 2 is a section taken on the line 70 II-II of Figure 1.

Figure 3 is a section taken on the line 75 III-III of Figure 1.

Figure 4 is a slightly different construction embodying the invention. 75

Figure 5 represents graphically the forces 80 acting on the armature at different deviations in the construction shown in Figure 1.

Figure 6 shows graphically the forces acting on the armature in the construction of 85 Figure 4.

Figure 7 illustrates a modification of the 85 means for applying a restoring force to the armature.

The magnet system is constituted by a permanent magnet 1 to which pole pieces 2 and 3 are attached. The pole pieces are shaped so as to form two air gaps providing two parallel but oppositely directed magnetic fields, see Figures 2 and 4. In these magnetic fields 90 an armature 6 is arranged which has its ends secured to a frame 7 extending on each side of the armature. The frame is secured at points 10 to springs 8 which are clamped at 11 and 12 by means of screws to a bracket 95 9 which is secured to the permanent magnet 1. The poles 2 and 3 have arranged between them a stationary coil 4 which surrounds the armature 6 and which is adapted to be traversed by electrical currents.

The frame has secured to it a stud 5 which may be connected directly to an oscillating member such as a loud speaker diaphragm.

The function of the magnet system is as follows:

A magnetic flux will be induced in the armature by the electrical current passing through the coil, said flux resulting, owing to the arrangement of the poles, in a movement of the armature in a direction determined by the magnetic field. The movement thus received by the armature will be a function of the magnetic force of the fixed magnets and that due to the polarization of the armature and of the acting force of the springs 8. The magnitude of these forces for different displacements of the armature is shown in Figure 5.

The abscissas designate the movement of the armature from its central position, the ordinates the forces exerted on the armature. In its central position the armature will be attracted at equal force by the north and south poles so that the forces exerted upon the armature by the magnetic field are equal to zero.

The armature is in a critical state of equilibrium as even the slightest displacement brings about a force in the direction of the nearest pole of the magnet. The magnetic force is known to change in a manner inversely proportional to the square of the distance between pole and armature so that the curve which represents the forces at any displacement from the center will be parabolic in form.

In the drawings this curve is designated by B.

The curve A represents the extent of the restoring forces exerted by the springs 8. These springs being clamped unilaterally the curve of the variation in the forces will be linear.

It is evident from Figure 5 that at the displacement *a* the force exerted by the permanent magnet is equal to the reaction force of the spring so that at a little added displacement in the direction of the pole the magnetic force overcomes the reactive force and the armature races and will adhere to this pole. At slight displacements, however, for example at those smaller than the displacement *b*, there will not be this probability and the resultant directing force will be about proportional to the deviation of the armature (see the cross-hatched piece). However, it will always be necessary to use a comparatively stiff spring in order to prevent the armature adhering to the poles.

In Figure 4 a construction is shown in which the springs 8 are very slack or resili-ent so that the force exerted by the springs increases upon displacement of the armature as designated in Figure 6 by A₁. In this figure B₁, again represents the force exerted

by the permanent magnet. This results immediately in a displacement of the point *a* to the left so that the probability of the armature adhering to the magnets is increased. To overcome this objection, each of the points 10 and 10' of the frame 7, see Figure 4, is connected by means of chords or wires 15 to fixed points 16 and 17.

As shown in Fig. 7, these wires or chords 15 are not tautly stretched and only come into operation when the armature has received a determined displacement. Thus, for example, in the case of displacement superior to c¹ (Figure 6) the restoring force (line A₁) will be reinforced by the tension of the wire (line C₁) so that the line A₁ shows a deviation D₁ at the point d¹ which shifts the danger point of the magnetic forces overcoming the reactive spring forces to the displacement e¹. The figure shows that for small displacements such as b¹ the force to be applied to secure displacement is comparatively small so that the system is highly sensitive. In the case of greater displacements this sensitivity will continue since the directing force required increases by very small values.

What we claim is:

1. A device for converting electrical oscillations into mechanical vibrations comprising an element having a normal position of equilibrium and adapted to move therefrom in response to said electrical oscillations, spring means for supporting said element, additional spring means not operatively associated with said element at its normal position of equilibrium, and means for operatively associating said additional spring means with said element after said element has moved a predetermined distance from its position of equilibrium, whereby said additional spring means influences the movement of said element only after a predetermined displacement of said element from its position of equilibrium.

2. A device for converting electrical oscillations into mechanical vibrations comprising a permanent magnet, an armature supported in the magnetic field of said permanent magnet and adapted to move in said field, a stationary coil surrounding said armature for carrying the electrical oscillations, said coil being adapted to polarize said armature in accordance with the electrical oscillations passing through the coil, a spring supporting said armature, and an additional spring for influencing the movement of the armature after a predetermined displacement of said armature from its position of equilibrium, said additional spring having no influence on the movement of said armature until it has moved the predetermined distance.

3. A device for converting electrical oscillations into mechanical vibrations comprising a permanent magnet, an armature sup-

ported in the magnetic field of said permanent magnet and adapted to move in said field, a stationary coil surrounding said armature for carrying the electrical oscillations, said coil being adapted to polarize said armature in accordance with the electrical oscillations passing through the coil, a spring for restoring said armature to its position of equilibrium, additional spring means inoperatively associated with said armature in its position of equilibrium, and means for operatively connecting said additional spring means with said armature after a predetermined displacement of the armature from its position of equilibrium.

4. A device for converting electrical oscillations into mechanical vibrations comprising a permanent magnet, an armature, a frame supporting said armature in the magnetic field of said permanent magnet, a stationary coil surrounding said armature for carrying the electrical oscillations, said coil being adapted to polarize said armature in accordance with the electrical oscillations passing through the coil, a pair of springs for supporting said frame, and additional springs for influencing the movement of the armature upon a predetermined displacement of said armature from its position of equilibrium, said additional springs being connected to said armature so that said armature is not influenced by said additional springs until the predetermined armature displacement occurs.

5. A device for converting electrical oscillations into mechanical vibrations comprising a permanent magnet, an armature supported in the magnetic field of said magnet in a position of equilibrium, a stationary coil surrounding the armature for carrying the electrical oscillations, said coil being adapted to polarize said armature in accordance with the electrical oscillations passing through the coil whereby said armature is moved from its position of equilibrium, means for restoring said armature to its position of equilibrium, and additional means for influencing the movement of the armature only after a predetermined displacement of the armature from its position of equilibrium.

6. A device for converting electrical oscillations into mechanical vibrations comprising a permanent magnet, an armature, a frame supporting said armature in a position of equilibrium in the magnet field of said magnet, a stationary coil surrounding the armature for carrying the electrical oscillations, said coil being adapted to polarize said armature to produce motion thereof in accordance with the electrical oscillations passing through the coil, means associated with said frame for restoring said armature to its position of equilibrium upon movement therefrom, additional means for applying a

restoring force to said armature, and means for operatively associating said additional means with said armature after said armature has moved a predetermined distance from its position of equilibrium.

7. A device for converting electrical oscillations into mechanical vibrations comprising a permanent magnet, an armature, a frame for supporting said armature in the magnetic field of said magnet in a position of equilibrium, a stationary coil surrounding the armature for carrying the electrical oscillations, said coil being adapted to polarize said armature in accordance with the electrical oscillations passing through the coil, flat springs for supporting said armature in its position of equilibrium, said flat springs being fixed to a rigid support at one end and to said frame at the other end, additional springs normally having no influence upon said armature, and means for connecting said additional springs to said frame to influence the movement of the armature after a predetermined displacement of the armature from its position of equilibrium.

8. A device for converting electric oscillations into mechanical vibrations comprising a ferromagnetic element, means for subjecting said element to the electromagnetic influence of the electric oscillations, means for providing two parallel but oppositely directed magnetic fields, a frame for positioning said element in the magnetic fields, and resilient means secured to said frame for supporting said frame for movement substantially parallel to the directions of said magnetic fields.

9. A device according to claim 8 characterized in that the frame consists of a rectangle, two parallel sides of which are connected by the element, and the midpoints of the other two sides of which are secured to the resilient means.

10. A device according to claim 8 in which the frame is supported by unilaterally clamped springs, characterized in that the clamping points of the springs are located on the same side of the frame relative to the axis of movement of the element and frame.

11. A device according to claim 8 in which the springs are slack, characterized in that the frame has secured to it one or more spring-like members which prevent an undesirably great deviation of the element from its central position.
